UNITED STATES PATENT OFFICE

136,256

DESIGN FOR A GAME BOARD

John R. Huckelbridge, Chualar, Calif.

Application June 1, 1943, Serial No. 110,339

Term of patent 14 years

To all whom it may concern:

Be it known that I, John R. Huckelbridge, a citizen of the United States, residing at Chualar, in the county of Monterey and State of California, have invented a new, original, and ornamental Design for a Game Board, of which the following is a specification, reference being had to the accompanying drawing, forming part thereof.

I claim:

The ornamental design for a game board, as shown.

JOHN R. HUCKELBRIDGE.
